(57) **CLAIM**

The ornamental design for a vehicle-mounted conduit carrier, as shown and described.

DESCRIPTION

FIG. 1 is a front perspective view of a vehicle-mounted conduit carrier, showing my new design, the environmental structure shown by broken lines forming no part of my design;

FIG. 2 is a left side elevation view;

FIG. 3 is a right side elevation view;

FIG. 4 is a top plan view;

FIG. 5 is a bottom plan view;

FIG. 6 is a front elevation view; and,

FIG. 7 is a rear elevation view.
